UNITED STATES PATENT OFFICE.

TIMOTHY B. SHUMAN, OF TYRONE, PENNSYLVANIA.

DESIGN FOR A TROUSERS-HANGER.

SPECIFICATION forming part of Design No. 33,762, dated December 18, 1900.

Application filed November 13, 1900. Serial No. 36,413. Term of patent 14 years.

To all whom it may concern:

Be it known that I, TIMOTHY B. SHUMAN, a citizen of the United States, residing at Tyrone, in the county of Blair and State of Pennsylvania, have invented and produced a new and original Design for a Trouser-Hanger, of which the following is a specification, reference being had to the accompanying drawings, forming part thereof.

Figure 1 is a side view, and Fig. 2 an end view, of a trousers-hanger embodying my new design.

The terminal portions A of the hanger are

bifurcated or provided with parallel arms which are angular in form and provided with 15 projections, as shown, and the body B is semi-circular and provided with a sharp or narrow bend located at one side of the middle.

What I claim is—

The design for a trousers-hanger, substantially as shown and described.

TIMOTHY B. SHUMAN.
